REMOTE CONTROL APPARATUS

Francis M. Schmidt, North Tonawanda, N. Y., and Gerald G. Smith, deceased, late of Kenmore, N. Y., by Myrtle Shandrew, administratrix, Kenmore, N. Y., assignors to The Rudolph Wurlitzer Company, Cincinnati, Ohio

Original application June 11, 1941, Serial No. 397,554. Divided and this application May 20, 1942, Serial No. 443,828

1 Claim. (Cl. 177—353)

This invention relates to a remote control apparatus which is particularly adapted to the selective control of automatic record changing phonographs but may be used for other purposes as well, and is a division of our application Serial No. 397,554, filed June 11, 1941.

Certain features of the apparatus disclosed herein are shown and claimed in co-pending application of Charles J. Hull and Fred H. Osborne, Serial No. 355,204, filed September 3, 1940.

One object of the present invention is to provide apparatus by means of which a controlled machine may be operated from a remote station which is connected only through the power mains which supply power for the controlled machine and for the remote station.

Another object of the invention is to provide remote control apparatus of this type which is able to discriminate accurately against spurious signals which might appear on the power lines and which might interfere with the operation of the controlled machine. For this purpose the controlling signals consist of a radio frequency carrier signal power modulated by a series of audio frequency impulses. The number of such impulses in a series determines the selective operation of the controlled machine and the impulses preferably occur at definitely timed intervals. Selectivity against spurious signals is obtained first by accurate tuning of the sending and receiving apparatus for a particular frequency of the carrier wave; second, by similar tuning for audio frequency impulses and third, by wasting a predetermined number of impulses at the beginning of each series. Preferably at least two such impulses are wasted—that is, a series of at least three impulses is required to effect any operation of the controlled machine. While one or possibly two spurious impulses of proper radio and audio frequency might possibly be impressed on a power line from some outside source, the chance of three such impulses properly spaced is very remote. The high degree of selectivity also insures against the unauthorized intentional operation of the machine by the generation of controlling impulses by other apparatus. Apparatus to produce the necessary impulses to operate the machine must be practically a duplicate of the authorized apparatus and must be similarly tuned.

Another means by which the apparatus discriminates against transient signals is by the use of suitable slow acting apparatus at the receiver which prevents operation by transient impulses of short duration.

Another feature of the invention resides in a particular manner in which the radio frequency carrier is modulated. This arrangement permits power modulation with a minimum number of tubes and parts.

Other objects and features of the invention will

be understood from the accompanying drawings and the following description and claim:

Fig. 1 is a diagram of electrical connections and apparatus illustrating a preferred form of remote control station. Fig. 2 is a similar diagram illustrating a preferred form of receiving apparatus. Fig. 3 is a perspective view of certain mechanical parts of the receiving apparatus with the stationary framework thereof omitted to show moving parts in more detail. Fig. 4 is a fragmentary view partly in section of a portion of the apparatus shown in Fig. 3. Fig. 5 is a diagram showing in conventional form the relation of the remote station, the receiver and a controlled machine to the commercial power circuits by means of which they are supplied and over which controlling signals are transmitted.

The invention is best adapted for use in a home or commercial establishment which is provided with the usual electrical wiring having suitable outlet sockets to which the controlled machine and the remote control apparatus may be connected by the usual socket plugs. For use in a commercial application such as a restaurant, the control will ordinarily be dependent upon the insertion of a coin. Obviously for home use the coin control may be omitted. In Fig. 5 there is shown a pair of conductors 10 which may be considered as the distributory conductors of a commercial power company leading to the premises on which the invention is to be used. Connected to the conductors 10 there is shown the usual local transformer 11 having a secondary winding connected to power mains 12 supplying the individual customer of the power company. Suitable cutout switches and overload protection, not shown, may be assumed to be connected between the transformer 11 and the mains 12. Appliance outlet sockets 13 are connected to the mains 12 in the usual manner and may be placed at any desirable position on the premises. Adjacent any one of the outlets 13 there may be installed a signal transmitter 14 having a cord 15 and socket plug 16 which may be connected to the socket 13. A signal receiver 17 having a cord 18 and plug 19 may be similarly connected to another of the sockets 13. The machine to be controlled is shown in Fig. 5 in the form of an automatic record changing phonograph 20 connected to the signal receiver by a cord 21. If desired, the receiver 17 may be placed within the cabinet of the phonograph 20.

Signal transmitter

For coin operation the signal transmitter 14 may be supplied with a coin slot 22 of any well known form adapted to receive a coin of a given denomination. Within the receiver there is provided a switch 23 (Fig. 1) which is momentarily closed upon the receipt of a coin in the coin slot

22. Many different forms of coin receiver and coin operated switches which may be used are known in the art and it is therefore unnecessary to describe the same in detail.

There is also provided a multi-point manual selector switch 24 which may be operated by a suitable knob 25 on the face of the transmitter 14. The switch 24 has a plurality of contact points 26 each connected by one of a group of conductors 27 with a corresponding point 28 on a motor driven multi-point switch 29. Other electrical apparatus within the transmitter 14 includes an electromagnetic relay 30 adapted when energized to close a series of normally open switches 31, 32 and 33 and a motor 34 adapted to operate the multi-point switch 29 and to rotate a series of cams 35, 36 and 37. The mechanical connections of the motor to the switch 29 and the respective cams are indicated schematically in Fig. 1 by broken lines and it is to be understood that these connections are such that each of the cams and the motor driven switch make one revolution in a definite period of time. The cams 35, 36 and 37 operate switches 38, 39 and 40, respectively. Said cams and switches and the switch 29 are shown in Fig. 1 in their initial idle position. Each cycle of motor operation starts with the parts in this idle position and continues until all of said parts are simultaneously returned to said position.

There are also provided electron discharge tubes 41, 42 and 43. Tube 41 is shown as a standard pentode tube and is used as a generator of radio frequency energy. Tube 42 is a twin triode tube. One of the triode elements is used as a radio frequency amplifier and modulator and the other as an audio frequency oscillator. Obviously two standard triode tubes could be used in place of the single tube 42. Tube 43 is shown as a diode tube connected as a half wave rectifier to supply the necessary D. C. plate voltages for tubes 41 and 42. In practice it is advantageous to combine the elements of tubes 41 and 43 in a single tube but separate tubes are illustrated in the drawings for the sake of simplicity.

Power for operating the transmitter is supplied from the plug 16 to a pair of line conductors 44 and 45, in one of which there may be placed a cutout switch 46. A transformer 47 has its primary winding connected to the line conductors 44 and 45 and its secondary winding arranged to supply current for the rectifier tube 43 and for a single lamp 48. One terminal of the secondary winding of transformer 47 is grounded and the opposite terminal is connected to the anode 50 of the rectifier tube 43. The cathode 51 of said tube is connected to a distributory conductor 52 which is maintained thereby at a suitable potential above ground and supplies the necessary D. C. potential for the plate circuits of tubes 41 and 42. A condenser 53 connected between the cathode and ground serves to smooth out the D. C. voltage.

The cathodes of the several tubes may be heated by heating elements connected to suitable taps on the primary or secondary windings of the transformer 47 in a conventional manner.

The remaining electrical apparatus illustrated in Fig. 1 may best be described in connection with the circuits in which they are included.

In the operation of the transmitter the switch 24 is first set on one of the points 26 by means of the knob 25. Each of the points 26 corresponds to an operation of the controlled machine and in the case of a selective record changing

phonograph each of said points corresponds to one of the records carried in the magazine of said phonograph. Obviously, as many such contact points as are needed may be used. In the drawings, for sake of simplicity, only eight are shown. The setting of the switch 24 may be indicated by a suitable scale visible to the operator and corresponding with a suitable index of record titles.

When the switch 24 has been properly set, a coin is deposited and switch 23 momentarily closed to complete a circuit from the line conductor 44 through switch 23, the winding of relay 30 and a resistance 49 to the line conductor 45. The consequent actuation of the relay 30 closes switch 31 which is in parallel with switch 23 and thus retains the relay in energized condition after switch 23 has been opened.

The operation of relay 30 also closes switch 32 and completes a circuit through said switch to start the motor 34. The first movement of the motor 34 operates the cam 35 to close switch 38 and short circuit the switch 32. The motor thus continues to operate until cam 35 has made a complete revolution and the parts have returned to idle position even though switch 32 is opened at a later time in the cycle of operation. The operation of motor 34 also actuates cam 36 to open switch 39 and break a normally closed circuit for the lamp 48. Said circuit leads from ground through switch 39, a resistor 54, lamp 48 and a portion of the secondary winding of transformer 47 back to ground. Switch 39 is not again closed until cam 36 has returned to idle position and thus the signal lamp 48 when lighted indicates that the motor 34 is not in operation.

The operation of motor 34 also rotates the finger 55 of the multi-point switch 29 in the direction of the arrow. In this rotation the finger 55 successively engages the contact points 28. When said finger reaches the point 28 connected to the point 26 on which the switch 24 is set, a shunt circuit is closed around the winding of the relay 30 and said relay is thereby deenergized. The provision of the resistor 49 prevents the formation of a dead short across the line conductors and thus serves as an overload protection. It will be apparent that the length of time during which the relay 30 is energized depends entirely upon the setting of the switch 24 and that after said relay is deenergized the finger 55 is returned to its normal idle position since the motor 34 continues to operate until cam 35 opens switch 38. During the operation of the motor the signal lamp 48 is not burning. When said lamp is again lighted at the end of a cycle of motor operation, it indicates that the apparatus is ready for the receipt of another coin.

The actuation of the relay 30 also closes switch 33 to start the operation of the radio frequency oscillator tube 41. Said tube is provided with a conventional anode-cathode circuit leading from the D. C. distributory conductor 52, through inductance 56 and tuning condenser 57 in parallel to the anode 58 and thence through the cathode 59 and switch 33 to ground. The grid-cathode circuit leads from cathode 59 to control grid 60 through resistor 61 and the parallel path formed by inductance 62 and condenser 63. Inductances 56 and 62 are coupled to give the necessary feedback for oscillation and the frequency of oscillation is controlled by the tuning condenser 57. Preferably oscillations of the order of 250 k. c. are used. Since switch 33 is included in the anode-cathode circuit, radio frequency energy is

generated in the circuits of said tube only when relay 30 is energized and switch 33 is closed.

The radio frequency energy generated in the tube 41 is amplified and power modulated by the tube 42 and associated circuits. In tube 42 the audio oscillator section consists of cathode 64, control grid 65 and anode 66. The radio frequency section of the tube consists of cathode 67, grid 68 and anode 69. The two cathodes 64 and 67 are connected together and are connected to ground through the lower half of a variable inductance 70 which is thus common to the cathode circuits of both sections of the tube. A condenser 71 serves as a radio frequency by-pass for the cathode circuits. The grid 65 is connected to the cathodes through a resistor 72 and to the inductance 70 through a resistor 73 and the switch 40. A condenser 74 is shunted across the inductance 70 to complete the audio frequency tuned circuit. The plate 66 is directly connected to the D. C. distributory conductor 52. The grid 68 is coupled to the grid of tube 41 through a condenser 75 and resistor 76. Inductance 77 serves as a radio frequency choke between grid 68 and the cathode circuits. Anode 69 is connected to the D. C. distributory conductor 52 through condenser 78, variable condenser 79 and inductance 80 all connected in parallel and together forming a radio frequency "tank."

In the electrical connections just described, the inductance 70 and condenser 74 form the tuned circuit of the audio frequency section of the tube 42. The grid 65 receives the necessary energy for oscillation from the tuned circuit, only when the switch 40 is closed. The lower portion of the inductance 70 also forms a part of the cathode circuit of the radio frequency section of the tube 42, so that the potential of the cathode 67 is affected by the oscillating current in the inductance 70. Thus the inductance 70 serves the dual purpose of producing oscillation and controlling the potential of the cathode 67 to modulate the radio frequency energy.

Radio frequency energy from tube 41 is fed to the grid 68 through the condenser 75 and resistor 76 and is amplified, modulated and impressed upon the tank circuit 78-79-80 by the radio section of tube 42. The switch 40 is operated by the cam 37, and said cam is so formed that the switch 40 is alternately opened and closed at regular intervals. The modulation of the radio frequency is thus given the form of a series of power impulses, the frequency of which is determined by the tuning of the resonant circuit 70-74. Preferably, said circuit is tuned to a frequency of the order of 400 cycles per second.

The inductance 80 is coupled with an inductance 81, connected in series with an inductance 82 and a condenser 83. The inductances 81 and 82, and the condenser 83 form a link circuit in which currents induced by the coupling with inductance 81 may be tuned by the condenser 83 to eliminate harmonics. The inductance 82 is closely coupled with an inductance 84 and loosely coupled with an inductance 85, and said coupling induces corresponding high frequency energy therein. One terminal of each of the inductances 84 and 85 is connected to the line conductor 44, and the opposite terminals of said inductances may be selectively connected to the line conductor 45 by a switch 86 connected to the last mentioned line conductor through a condenser 87.

By means of the connections just described, the amplified and modulated radio frequency out-

put of tube 42 is impressed upon the line conductors 44 and 45 by either one of the inductances 84 and 85, the particular one of said inductance to be used being chosen by manual operation of the switch 86, and the choice depending upon the impedance of the external circuit between the remote station and the local station and consequent strength of signal required.

The cam 37 and the switch 29 are both operated by the motor 34 and the audio frequency impulse produced by the operation of switch 40 may thus be accurately timed with relation to the movement of switch 29. It will be noted that in the movement of switch 29 from the initial idle position, the finger 55 travels some distance before the first of the contact points 28 is reached. Preferably, the cam 37 is so shaped that it produces three audio impulses during this time. Thus three audio impulses are generated and impressed upon the line conductors before the finger 55 reaches the first of the contact points 28. During the movement of the finger 55, between each of the succeeding contact points, an additional audio frequency impulse is produced. Thus, if the switch 24 is set on the contact point 26 corresponding to the first of contact points 28, a series of three audio frequency impulses is transmitted before the relay 30 is deenergized to stop the production of radio frequency oscillation. Similarly, the setting of the switch 24 on any one of the other contact points 26, results in the production of a series of impulses of correspondingly greater number.

Receiver

Power for operating the receiver 17 and the controlled machine 20 is supplied from the plug 19 to a pair of power lines 100 and 101 in one of which there may be included a cut-out switch 102. A transformer 103 has its primary winding connected to the power lines 100 and 101 and has the terminals of its secondary windings connected to the anodes of a rectifier tube 104. The cathode of said tube is connected to a D. C. distributory conductor 105 which is grounded through a resistor 106. The mid-point of the secondary winding of the transformer 103 is connected to a conductor 107 which is grounded through a resistor 108. The rectifier tube 104 thus serves as a full wave rectifier to maintain a suitable D. C. potential difference between conductors 105 and 107. The resistances 106 and 108 are so chosen that conductor 105 carries a suitable potential for the plate circuits of the several tubes used in the receiver and the conductor 107 carries a negative potential.

The electrical apparatus of the receiver also includes a radio frequency transformer 109, a pentode tube 110 used for radio frequency amplification, a radio frequency transformer 111, a tube 112 having a diode rectifier section and a triode amplifier section used for audio frequency amplification and a similar tube 113. Other electrical elements shown in Fig. 2 will be described in connection with the circuits in which they are included.

The primary winding of the transformer 109 is connected to the line conductors 100 and 101 through condensers 114 and 115 adapted to transmit radio frequency energy but to block the usual 60 cycle commercial current. Thus the modulated radio frequency signals generated in the transmitting apparatus are conducted from the transmitter 14 through the line conductors 12 and line conductors 100 and 101 to the trans-

former 109 and said signals induce corresponding currents in the secondary winding of said transformer. A tuning condenser 116 is connected in parallel with the secondary windings of the transformer 109 to complete a resonant circuit which may be tuned to the radio frequency of the incoming signals. The resulting signal is impressed on the control grid 117 of tube 110. The cathode 118 of tube 110 is connected to ground through a conventional blazing resistor 119 and condenser 120 and the anode 121 of said tube is connected to the positive D. C. distributory conductor 105 through a tuned circuit consisting of the primary winding of transformer 111 and a tuning condenser 122. The connections just described constitute a conventional stage of radio frequency amplification by means of which the incoming signals are amplified and impressed upon the primary winding of transformer 111.

The secondary winding of transformer 111 is provided with a tuning condenser 123 in parallel therewith to complete a tuned secondary circuit, one terminal of which is connected to the anode 124 of the rectifier section of tube 112. The opposite terminal of said tuned circuit is connected to the cathode 125 of said tube through resistors 126, 127 and 128. The D. C. voltage produced in the circuit just described by operation of the rectifier section of tube 112 appears across the resistors 126, 127 and 128 and is applied to the control grid circuit of tube 110 through a conductor 129 and a filter network consisting of a resistor 130 and condensers 131 and 132 to provide automatic volume control.

The control grid 133 of the amplifier section of tube 112 is connected through a coupling condenser 134 to a point in the rectifier circuit just described where suitable variations in voltage are obtained for the operation of said amplifier section. Said grid is connected to ground through a conventional grid coupling resistor 134A. The cathode 135 is connected to cathode 125 and is biased to ground in a conventional manner. The anode 136 is connected to the D. C. distributory conductor 105 through a resistance 137. The connections just described complete a conventional stage of audio frequency amplification as a result of which a pulsating current of audio frequency corresponding to the transmitted impulses is generated in the circuit of anode 136.

The anode 136 is coupled by means of a condenser 138 to a circuit consisting of a variable inductance 140 and condenser 141 connected in parallel and a high frequency choke 145 and resistor 146 connected in series therewith and connected to the negative D. C. conductor 107. In this circuit the inductance 140 and condenser 141 form a tuned portion which may be adjusted to the particular frequency of the signal impulses. Voltages due to the signal impulses appear across the tuned portion of the circuit while voltages due to transient higher frequency energy appear across the choke 145 since its impedance to high frequency current is high as compared to that for lower frequency currents.

A rectifier circuit consisting of the rectifier anode 139, cathode 144, resistor 142 and condenser 143 is connected in parallel with the tuned portion of the circuit just described, but the connection is exclusive of the choke 145. Current flow in the rectifier circuit is thus controlled by the low frequency voltages across the tuned portion and is substantially unaffected by higher frequency voltages across the choke 145. This arrangement therefore provides an additional

valuable means for discriminating against transient or spurious signals.

The current appearing in the rectifier circuit just described is a pulsating direct current of a predetermined audio frequency and flows only during the brief period of each of the signal impulses. During each impulse, the upper or cathode end of the resistor 142 is at a considerably higher potential than the lower end. The lower end of said resistor is connected through choke 145 and resistor 146 to the negative D. C. conductor 107 and the opposite end of said resistor is connected to the control grid 147 of the second section of tube 113. The cathode 148 of said second section is grounded and the anode 149 is connected through the winding of a relay 150 to the positive D. C. conductor 105. Because of the negative potential of the conductor 107 which is impressed upon the grid 147 when no current flows in the rectifier circuit, the second section of tube 113 is normally biased to cutoff and no anode current is drawn. During the receipt of a signal impulse, the voltage appearing across the resistor 142 raises the potential of the control grid 147 sufficiently to permit current flow in the anode circuit to energize the relay 150. Thus, said relay is momentarily energized in response to each of the signal impulses.

The relay 150 preferably is adjusted for relatively slow action by use of a copper core or other well known means so that transient impulses of short duration cannot energize the relay. However, the speed of operation of the relay is not reduced sufficiently to prevent a distinct actuation for each signal impulse and a distinct release of the relay between the impulses.

Referring now to Figs. 3 and 4, there is illustrated therein certain mechanical apparatus forming a part of the receiver and actuated by operation of the solenoid 150. In said figure only movable parts of the apparatus are shown and it will be understood that said parts may be supported on any suitable stationary structure. Said apparatus includes a shaft 160 carrying a contact finger 161 adapted to engage a series of contact points 162 as the shaft 160 is rotated in the direction of the arrow. The shaft 160 also carries a ratchet wheel 163 and is urged in the clockwise direction by a torsion spring 164, one end of which is secured to said shaft and the opposite end to a part of the stationary structure. An electromagnet 165 is mounted in a stationary position and is adapted to attract an armature 166 which is pivotally mounted on a pin 167. A finger 168 is pivotally mounted by means of a pin 169 on the armature 166 and is held against a stop pin 170 by a tension spring 171, the end of which is anchored to a stationary portion of the apparatus. The finger 168 is in position to engage the teeth of the ratchet wheel 163 and to move the ratchet wheel a distance corresponding to one tooth each time the magnet 165 is energized. A pawl 172 is mounted on a pivot pin 173 and may be held in engagement with the teeth of the ratchet wheel 163 by a tension spring 174. Said pawl is adapted to hold the ratchet wheel in the positions in which it is placed by operation of the magnet 165.

A lever arm 176 is adapted to engage the tail of the pawl 173 and to disengage the same from the teeth of the ratchet wheel. Said lever arm is pivotally mounted within a time delay device 177 which may be of a common commercial form, the details of which form no part of the present

invention. It is sufficient to say that the device has an action somewhat similar to that of a dashpot. That is, the lever arm 176 may be rapidly lifted by a small force in opposition to the action of a tension spring 178. When the lifting force is withdrawn, the spring 178 returns the lever 176 to its lower position but the time delay device 177 operates to slow the return movement to a predetermined slow speed which may be adjusted as desired. For lifting the lever arm 176 there is provided a vertical rod 179, the upper end of which is pivoted to the lever arm 176 and the lower end of which is reduced and extends through a loosely fitting opening in the armature 166, as shown in Fig. 4.

In the normal idle position of the apparatus, the lever arm 176 is held in its lower position by the spring 178 and engages the pawl 172 to free the same from the ratchet wheel 163. Said ratchet wheel carries a stop pin 180 engaging a suitable stationary stop 181 which holds the ratchet wheel in an initial idle position when the pawl 172 is disengaged therefrom. In this position the contact finger 161 is out of engagement with the contact points 162 and is positioned at a sufficient distance from the first of said contact points so that three actuations of the magnet 165 are required before said contact finger reaches said first contact point. Each actuation of the magnet 165 moves the ratchet wheel 163 and the contact finger 161 one step in the counterclockwise direction. The first such actuation causes the lever arm 176 to be lifted free of the pawl 172 and permits said pawl to hold the ratchet wheel. After each actuation of magnet 165 the slow downward movement of the lever 176 is begun but each succeeding actuation returns said lever to its upper position. Thus, if a series of actuations of the magnet 165 occurs with sufficient frequency the time delay device 177 prevents the arm 176 from freeing the pawl 172 between actuations. At the end of a series of such actuations, the lever arm 176 moves slowly downward and eventually engages the pawl 172, releasing the same from the ratchet wheel and permitting the ratchet wheel to return to normal idle position.

Referring again to Fig. 2, the relay 150 actuates a switch 162 to close a circuit from line conductor 100 through magnet 165 to the line conductor 101. The switch 162 is closed each time the relay 150 is energized. Thus the magnet 165 acts as a repeater for the relay 150 and is momentarily actuated in response to each signal impulse received from the transmitter. The lever 176 in its uppermost position is adapted to engage and operate a pair of switches 183 and 184, the switch 183 being closed, and the switch 184 being opened when so engaged. Said switches are preferably adjusted so that in the upward and downward movement of the lever arm 176 each of said switches is closed before the other is opened. The switch 183 when closed completes a circuit from the power lines 100 and 101 for a relay 185. Said relay when actuated closes a switch 186.

In the operation of this portion of the apparatus, the first signal impulse received causes an actuation of magnet 165 to lift the lever 176 to close switch 183 and thereafter open switch 184. The operation of switch 183 energizes the relay 185. The movement of the lever 176 in the upward direction is relatively rapid so that switch 184 is opened before relay 185 has closed switch

186. Since all relays require an appreciable time for operation, it is not always necessary that an especially slow acting relay be used for operation of switch 186. However, a slow acting relay may be used if necessary since it is desirable to open switch 184 before switch 186 is closed. At the end of a series of signal impulses, the contact finger 161 has been placed by operation of magnet 165 on one of the contact points 162. In this connection it is to be noted that the initial position of said contact finger is sufficiently far from the first of the contact points 162 so that a series of three impulses is required before said finger reaches the first of said contact points. Thus each of the contact points 162 corresponds to one of the contact points 26 and the point 162 selected by operation of magnet 165 is determined by the setting of switch 24.

The cessation of signal impulses permits the lever 176 to move slowly downwardly. In this movement the switch 184 is closed considerably before switch 183 is opened. The operation of switch 184 completes a circuit from line conductor 100 through switch 184 and switch 186 to the contact finger 161 and thence from the selected contact point 162 to one of a series of electromagnets 158, each of which has its opposite terminal connected to the line conductor 101. At the same time, a circuit is completed through the switches 184 and 186 for an electromagnet 158. The electromagnets 158 and 175 form part of a controlled machine which may be of the type disclosed in Wilcox Patent No. 2,002,236 and the magnets 158 and 175 may correspond to the magnets 158 and 175 in said Wilcox patent. In that patent each of the magnets 175 controls the selection of a predetermined record and the magnet 158 initiates one operation of the machine. For selection of the record and initiation of the operation only momentary actuations of the magnets 158 and 175 are required. As the downward movement of lever 176 continues, switch 163 is opened to deenergize magnet 185. Switch 186 is thereby opened to break the circuits of the magnet 158 and the particular magnet 175 which is energized.

From the foregoing specification it will be seen that the invention provides an impulse type of remote control apparatus peculiarly discriminatory against stray signals and therefore well suited to the transmission of its signals over commercial power lines. The invention has been described in one of its preferred forms, the details of which may be varied between wide limits without departing from the scope of the invention as defined by the appended claim.

The invention claimed is:

In a remote control receiver adapted to receive signals in the form of a high frequency carrier modulated by lower frequency power impulses, the sub-combination of a parallel tuned circuit tuned to the low frequency of said power impulses, a high frequency choke, connections applying demodulated signal energy across said tuned circuit and said choke in series, a rectifier circuit connected in parallel with said tuned circuit exclusive of said choke, and means utilizing current flow in said rectifier circuit to control operation of said receiver.
